UNITED STATES PATENT OFFICE.

ANDREW P. SCHMITT, OF MIDDLE VILLAGE, NEW YORK.

ASH-SIFTER.

1,242,050.

Specification of Letters Patent.

Patented Oct. 2, 1917.

Application filed February 27, 1917. Serial No. 151,319.

To all whom it may concern:

Be it known that I, ANDREW P. SCHMITT, a citizen of the United States, residing at Middle Village, in the county of Queens and 5 State of New York, have invented new and useful Improvements in Ash-Sifters, of which the following is a specification.

This invention relates to sifters and screens, and more especially those to be used 10 in the household; and the object of the same is to produce an improved ash sifter which has means within a single casing for moving the screen after the ashes have been sifted out, and dumping from the screen the siftings which remain in the form of particles 15 of coal suitable for subsequent use.

The object is carried out by constructing the device in a manner hereinafter more fully described and claimed, and as shown 20 in the drawings wherein:

Figure 1 is a vertical longitudinal sectional view of this device with the parts in the position they assume while sifting is being done.

25 Fig. 2 is a partial section of the same showing the parts in the position they assume when the siftings are being dumped from the screen.

Fig. 3 is a cross-section on the line 3--3 of Fig. 1.

The numeral 1 designates broadly the casing or box whose entire top 2 may be movable to gain access to the interior, but in any event the rear portion of this top has an 35 opening 3 preferably closed by a hinged cover 4 for a purpose yet to appear. Internally the walls of the casing may converge toward the bottom as shown at 5 to form two hoppers whose mouths deliver respectively 40 into the ash pan A and the coal pan C as indicated in Fig. 1 only. Between these mouths 6 and 7 the casing has an interior upright partition 8 provided with a large opening 9 as best seen in Fig. 3. The casing 45 may be of any suitable material and appropriate size.

The numeral 10 designates a cylindrical screen of wire of appropriate mesh whose 50 front end is closed by a head 11 and whose rear end is open and preferably strengthened by a reinforcing band 12, and at one side of the body of this screen is a hinged door 13, while its interior preferably carries an oblique baffle 14 also of screen wire and inclining from its closed head 11 to its mouth 55 as best seen in Fig. 1. At the center of the

head 11 is an opening surrounded by a spider or plate 16, and secured to the latter is a tubular shaft, 17 which extends through the large opening 9 and along the compartment 60 D of the casing as seen in Fig. 1, is journaled through its remote end as at 18 by means of a small hole which permits the shaft to rotate or to slide, and carries a crank handle 19 on its outer extremity. 65

The rear head 21 of the screen is solid, somewhat larger than the front head 11, and provided with a peripheral flange 22 of a size to inclose the reinforcing band 12 as shown, and to the center of this rear head is 70 secured a spider or plate 26 from which projects a tubular shaft 27 of a size to pass loosely through the tubular shaft 17 and even beyond its crank handle at times, and itself having a projection or handle 29. 75 Thus it will be seen that the body 10 and one head 11 of the screen are carried by the outer tubular shaft 17, whereas the other head 22 thereof is carried by the inner tubular shaft 27, and the shafts are telescopically and rotatably mounted one upon the other, the outermost having its bearing within the journal 18 and the innermost having its bearing in the outermost.

The numeral 27 designates a rod preferably extending through the rear wall of the casing 1 and secured thereto by means of a plate 36, and from this plate the rod extends throughout the length of the inner shaft 27, than which it is sufficiently smaller so that said shaft may rotate or slide upon the rod. The latter therefore affords a support for the rear ends of the telescopic shafts, no matter what their position within the casing 80 as described below. When the plate 36 is disconnected from the outer face of the casing, the entire rod may be removed therewith so as to permit a separation of parts if it should become necessary. 95

With the above construction of parts, the 100 operation is as follows: Two ordinary cans are placed under the mouths 6 and 7 of the casing, the can A being for ashes which will fall from the sifting compartment S to the left of the partition 8, and the can C for siftings or coal which will fall from the dumping compartment D to the right of said partition. The crank handle 19 is now pushed inward so that the screen 10 stands within the sifting compartment as shown in Fig. 1, the cover 4 is raised, the weight of the baffle 14 causes the screen to stand with 105 110

- its cover 18 uppermost, and this cover is raised so that a charge of coal and ashes as taken from the furnace is put into the screen. The covers are now closed, and the operator 5 turns the screen by means of the crank handle. The ashes are sifted out of the coal and fall through the screen into the compartment S, and thence through the mouth 6 into the ashcan A, and all dust raised is confined within the casing. After a suitable 10 time, the operator draws on the projecting handle 29, with the result that both shafts and the screen move along the rod 37 until the rear head 22 strikes the partition 18 15 around the opening 9 therein and closes the same. Then the operator grasps and draws on the handle 19 until the outer shaft 17 slips along the inner shaft 27 and the screen body 10, moves upon the inner shaft with its 20 open end at 12 spaced from the opening 9 and the head 22, and its closed end or head 11 adjacent the front wall of the casing. There is thus exposed a certain space between the mouth of the screen and the partition, and now when the operator rotates the 25 screen by its crank handle the siftings or coal yet within the screen, falls out the mouth—the baffle assisting in its agitation and delivery—through the compartment D 30 and into the coal can C; and again what dust arises is confined within the casing in a manner which will be clearly understood. Now by pushing all handles inward as far as possible, the parts are caused to resume 35 the position shown in Fig. 1, when the covers may be raised and a new charge put into the screen and the operation repeated. It will be observed that the compartment D wherein dumping occurs must be longer 40 than the compartment S wherein sifting occurs. The latter may only be of a length sufficient to receive the screen and both its heads, whereas when the screen is drawn into the dumping compartment away from 45 its rear head, it must be capable of being moved sufficiently far therefrom to uncover a space out of which the siftings or coal may be delivered. Of course it would be possible to elongate the bearing at 18 and omit the 50 rod 37, but by having the telescopic shafts 17 and 27 both tubular, the bore of the smaller shaft affords an opening through which may pass a rod 37 whose rear end finds support as at 36 on the rear wall of the 55 casing, and therefore the several axial members are very well supported by simplest means, and yet can be detached from the casing and removed when desired.
- What is claimed as new, is:—
- 60 1. In an ash sifter, the combination with a casing having a partition dividing its interior into two compartments of unequal length and provided with a large opening, an outlet at the bottom of each compartment, 65 and a filling opening at the top of the
- smaller compartment closed by a cover; of a rod secured to the rear wall of the casing, projecting centrally through said opening, and extending approximately to the front wall, the latter being provided with a hole 70 concentric with the rod, a two-part tubular shaft whose inner part is rotatably and slidably mounted on the rod and whose outer part is rotatably and slidably mounted on the inner part and both of which parts extend through said hole, a crank handle on the outer part beyond the front wall of the casing, a screen having a cupped body of a size to pass through the opening of the partition, and whose bottom is mounted rigidly 75 on said outer part, a closure for the mouth of the screen mounted on the inner part and of a size to contact with the partition around the opening therein when drawn against it, a baffle within the screen, and a door in one 80 side of the same registering with the cover in the casing.
2. In an ash sifter, the combination with a casing having a partition dividing its interior into two compartments of unequal 85 size, the partition being provided with a large opening, an outlet at the bottom of each compartment, and a filling opening at the top of the smaller compartment, of a rod secured to the rear wall of the casing, projecting centrally through said opening, and extending approximately to the front wall, the latter being provided with a hole concentric with the rod, a two-part tubular shaft 90 whose inner and longer part is rotatably and slidably mounted on the rod and whose outer and shorter part is rotatably and slidably mounted on the inner part and both of which parts extend through said hole, operating means on the outer part beyond the 95 front wall of the casing, a screen having a substantially cylindrical body of a size to pass through the opening in the partitions, and a closed bottom mounted rigidly on said outer part and, a head for the open end of the screen mounted on the inner part and adapted to close the mouth of the screen and a door in one side of the screen body adapted to register with the filling opening of 100 the casing.
3. In an ash sifter, the combination with a casing having a partition dividing its interior into two compartments and provided with a large opening, an outlet at the bottom of each compartment, and a filling opening at the top of the rear compartment closed by a cover and a bearing in its front wall; of a two-part telescopic shaft rotatably and slidably mounted through said bearing, a crank handle on the outer part of said shaft beyond the front wall of the casing, a substantially cylindrical screen body, a closed bottom therefor mounted rigidly on said outer part and of a size to pass 110 through the opening in the partition, a 115
- 120
- 125
- 130

- head for the open end of the screen body mounted on the inner part of said shaft and of a size to contact with the partition around the opening therein when drawn against it, and a door in one side of the body registering with the cover in the casing.
4. In an ash sifter, the combination with a casing having an upright partition dividing its interior into two compartments and 10 provided with a large opening, an outlet at the bottom of each compartment, and a filling opening in the casing; of a guide on the rear wall of the casing, a two part tubular shaft whose inner and longer part is rotatably and slidably mounted on the guide and
- whose outer and shorter part is rotatably and slidably mounted on the inner part and both of which parts extend through the front wall of said casing, handles at the front ends of said parts beyond the front wall of 20 the casing, a screen having a cupped body of a size to pass through said opening and a closed bottom mounted rigidly on said outer part, and a closure for the mouth of the screen mounted on the inner part and of a 25 size adapted to close against said partition around the opening therein.

In testimony whereof I affix my signature.

ANDREW P. SCHMITT.
